UNITED STATES PATENT OFFICE.

JOHN T. ROWLANDS, OF RACINE, WISCONSIN.

HORSE-COLLAR FASTENING.

SPECIFICATION forming part of Letters Patent No. 364,375, dated June 7, 1887.

Application filed February 10, 1887. Serial No. 227,160. (No model.)

To all whom it may concern:

Be it known that I, JOHN T. ROWLANDS, a citizen of the United States, residing at Racine, in the county of Racine and State of Wisconsin, have invented certain new and useful Improvements in Horse-Collar Fasteners and Strap-Holders; and I do hereby declare the following to be a full, clear, and exact description of the invention, such as will enable others skilled in the art to which it appertains to make and use the same.

My invention relates to horse-collar fastenings; and it consists of a certain construction and arrangement of a coupling to be attached to the lower end of a horse-collar, by means of which the two parts of the collar may be readily locked together and as readily detached.

In order that my invention may be clearly understood, I have illustrated in the annexed drawings one form thereof which I have used with practical success, and which will be fully described in the ensuing specification, and particularly pointed out in the claims at the close thereof.

Referring to the drawings, Figure 1 represents an elevation of so much of a horse-collar as will suffice to illustrate the application of my invention. Fig. 2 is a perspective view of the two parts composing my coupler. Fig. 3 represents a vertical longitudinal central section of the coupling, the two parts being shown in their locked position. Fig. 4 represents an end elevation of the couplers, looking in the direction of the arrow, Fig. 3.

The coupling consists of the two socket-castings A and B, each of which has an open and a closed end. The open ends *a* and *b* of the respective socket-castings are adapted to receive the respective ends, *C* and *D*, of the collar, and which ends may be secured in any suitable or convenient manner. The closed end *a'* of the socket-casting A is constructed with an elongated opening, *A'*, for the reception of a projection, *B'*, cast or otherwise formed on the closed end *b'* of the socket-casting B. This projection *B'* is constructed in the form of a flat staple, with its edges and corners chamfered to admit of its free insertion in the opening *A'*, and it is of such dimensions at the point where it connects with the casting B

that when it is inserted in said opening it will fit snugly therein.

The casting A is constructed with a slot on its under side, through which passes a lever, 55 E, which lever lies adjacent to the closed end *a'* of the casting, and is pivoted to said casting at *e*. The lower end of this lever is constructed in the form of a loop, *d*, and the upper end thereof is constructed in the form of a tongue, 60 *e'*, adapted to enter the opening *c* in the projection B'. The under side of the lever E is so shaped that a portion of said lever, when in its locked position, will lie flush with a part of the under surface of the socket-casting engaged by the hames.

It will be readily seen that when it is desired to lock the couplings together it is only necessary to insert the projection B' in the opening A' and turn the lever E from the position shown in dotted lines to the position shown in full lines, Fig. 4, when the tongue *e'* of lever E will pass up through the opening *c* in the said projection and hold the same firmly in place.

The socket-casting B is provided on its under side with a lug, *f*, to which is pivotally secured a loop or strap-holder, *d'*. It will be observed that the loops *d* and *d'* not only serve as strap-holders, but also serve to prevent the hames from slipping from the collar.

It will also be observed that in my construction I avoid the use of any spring construction to hold the tongue *e'* in engagement with the projection B'.

The lever E will, in all ordinary conditions, be kept in a closed position, even if the hames are not upon the collar; but when the martingale is attached to the loop *d*, or the hames are fastened in place, the lever is held beyond the possibility of movement.

What I claim, and desire to secure by Letters Patent, is—

1. The combination, substantially as before set forth, of the socket-castings, a projection 95 on one of said castings having an opening therethrough, an opening corresponding to the projection in the other casting for the reception of said projection, and a pivoted lever having a part passing through the opening in 100 said projection.

2. The combination, substantially as before

set forth, of the socket-castings, the projection on one of said castings, a corresponding opening in the other casting for the reception of said projection, and a pivoted lever engaging the opening in said projection, a portion of said lever, when closed, lying flush with a part of the under surface of the socket-casting engaged by the hames, all arranged to operate substantially as described.

10 3. A collar fastener composed of two socket-castings, each of which is provided with a loop or strap-holder, one of said strap-holders be-

ing on a lever locking the two castings together, the arrangement being substantially as described, whereby, when placed in operative 15 position, one of said strap-holders is on the front edge and the other on the rear edge of the collar, as set forth.

In testimony whereof I affix my signature in presence of two witnesses.

JOHN T. ROWLANDS.
